(57) **CLAIM**

The ornamental designs for output device back box, as shown and described.

DESCRIPTION

FIG. 1 is an isometric view of the present design;

FIG. 2 is a top plan view of the embodiment of FIG. 1;

FIG. 3 is an elevational side view of the output device back box of FIG. 1 from a first orientation;

FIG. 4 is an elevational side view of the output device back box of FIG. 1 from a second orientation;

FIG. 5 is an elevational side view of the output device back box of FIG. 1 from a third orientation; and,

FIG. 6 is an elevational side view of the output device back box of FIG. 1 from a fourth orientation.

The bottom view has not been illustrated. This view is unadorned and not part of the invention.
